(57) **CLAIM**

The ornamental design for a front trunk for a vehicle, as shown and described.

DESCRIPTION

FIG. 1 is a perspective view of a front trunk for a vehicle. FIG. 2 is another perspective view of a front trunk for a vehicle.

FIG. 3 is a front elevational view of the front trunk for a vehicle of FIG. 1 and FIG. 2.

FIG. 4 is a back elevational view of the front trunk for a vehicle of FIG. 1 and FIG. 2.

FIG. 5 is a right side elevational view of the front trunk for a vehicle of FIG. 1 and FIG. 2.

FIG. 6 is a left side elevational view of the front trunk for a vehicle of FIG. 1 and FIG. 2.

FIG. 7 is a top plan view of the front trunk for a vehicle of FIG. 1 and FIG. 2.

FIG. 8 is a bottom plan view of the front trunk for a vehicle of FIG. 1 and FIG. 2; and,

FIG. 9 is a perspective view of the front trunk for a vehicle of FIG. 1 and FIG. 2 as part of a semi-truck cab.

The items shown with broken lines form no part of the claimed design.
